UNITED STATES PATENT OFFICE.

ROBERT A. PORTERFIELD, OF BALTIMORE, MARYLAND, ASSIGNOR TO PRUDENTIAL OIL CORPORATION, OF NEW YORK, N. Y., A CORPORATION OF DELAWARE.

SIDE-FURNACE OIL STILL.

Application filed March 12, 1921. Serial No. 451,674.

The invention is a side furnace oil still, so constructed, first, that the bottom of the still is heated uniformly over its exposed area, and, second, that said bottom is prevented from becoming unduly expanded or attaining a permanent sag by reason of said heating.

In the accompanying drawings—

Fig. 1 is an elevation of the front of my 10 side furnace oil still, the right hand portion being broken away and in vertical section. Fig. 2 is a partial section in plan on the line 2, 2 of Fig. 3. Fig. 3 is a vertical transverse section on the line 3, 3 of Fig. 2.

15 Similar numbers of reference indicate like parts.

4 is the cylindrical still closed at both ends and having the usual man-holes 5 and pipe connections 6. The setting of masonry is 20 here quadrangular in form, with end walls 7, 8 and front and rear side walls 9 and 10. Secured diametrically opposite on the exterior of the still are brackets 11, Fig. 3, which rest upon the upper ends of vertical channel 25 bars 12. Said bars and brackets are imbedded in the masonry of the side walls. On the exterior of said side walls are a number of channel bars 13 which are connected to the channel bars 12 by bolts 14 extending 30 through and also imbedded in the masonry of said side walls.

In the side wall 9 are recesses 15, Fig. 2, which communicate with the furnaces which are formed as follows: Within the space enclosed by the side and end walls is a longitudinal bridge wall 16, between which and the front side wall 9 are four transverse fire-brick partitions 17 which rest upon masonry bases 18, Fig. 1, so that, in the construction 40 illustrated, five fire-chambers 19 are thus produced. In each of said chambers is a grate 20, Fig. 3, supported at its rear end upon a low wall 21, and at its front end upon a plate 22, above and below which plate are 45 respectively the firing opening 23 and the ash pit opening 24, these openings communicating with the corresponding recess 15 in the side wall 9.

Between the bridge wall 16 and the rear 50 side wall 10 is a partition 25 which forms the bottom of a horizontal flue 26 closed at one end by the end wall 8 and extending at the other end 27 through the end wall 7, Fig. 1, and communicating with the stack or 55 chimney. This flue is covered at its ends

by plates 28, Fig. 2, of fire-brick, and by separated plates 29 of similar material. The intervals between the cover plates 29 are disposed so that the gas current from each of the furnaces passes through one of said 60 intervals to the escape flue. That is to say, the products of combustion from each furnace, as for example 19* in Fig. 2, pass from the grate and over the bridge wall 16 to the interval α which is in line with that furnace 65 and then downward through that interval to the common flue 26, and so to the stack. Each furnace, therefore, may be fired and operated independently of the others, and each furnace acts upon the limited area of 70 the still bottom which is directly above it and included between the adjacent partitions 17 or partitions 17 and adjacent end walls 8, 7 which bound the fire chambers of the several furnaces.

Particular attention is now directed to the fact that while the still 4 at its ends rests on the end walls 7, 8, there is normally no contact between the bottom plates of the still and the partitions 17; but, on the contrary, there is a clearance 30 between the still bottom and the top surfaces of the partitions which are recessed to conform to the contour of and to receive said bottom. The depth of this clearance will depend upon the 80 dimensions of the still. To take an illustration from actual working conditions now existing in a steel still built in accordance with the foregoing description, said still is forty feet long and fourteen feet in diameter, 85 and the clearance 30 is about three quarters of an inch in depth.

The object of this construction is as follows:

Hitherto difficulty has been experienced in 90 applying heat with proper uniformity to long stills of the kind referred to and moreover, the long still being supported from below only at its extremities, its bottom plates sag downward in the middle portion not only 95 by reason of the weight of the charge, but also by reason of the circumferential expansion of said plates under the high heat employed. This heat is commonly from 1000° to 1200° Fahr., bringing said plates to a dull 100 cherry red and causing a lowering of the elastic limit of the metal, which is more or less indeterminate, and which is very apt to result in a permanent sag of the still bottom.

By making the side furnaces separate and 110

independent of one another and by compelling the combustion products of each furnace to pass through a separate opening or downtake to the common flue 26 beneath, the 5 gas currents are all caused to move transversely across and under the still bottom and parallel to one another. Thus the heating effect of each separate furnace is confined to a definite fractional area of the still bottom 10 immediately over that furnace; and so by equalizing said heating effects of the several furnaces, the whole exposed still bottom is subjected to uniform heating.

The clearances 30 effectively prevent any 15 excessive or permanent sagging of the still bottom because they are to be proportioned so that the bottom plates will close them and meet the partitions, and so become seated thereon before any detrimental expansion or 20 permanent set can take place. After the bottom plates have thus become supported, the space between adjacent partitions 17 is, in the illustration above given, only about six feet, over which distance any possible def- 25 ormation of the still bottom due to expansion is negligible. I have thus done away with both of the difficulties before men-

tioned, and I have produced a side furnace oil still which is heated uniformly over its exposed bottom, and which undergoes no 30 substantial or material deformation or sagging by reason of the heat applied.

I claim:

An oil still of the type set forth, a setting therefor having side and end walls, a plurality of transverse partitions in the space enclosed by said walls, a plurality of heating furnaces respectively disposed in the several compartments bounded by said partitions and having their fire-chambers directly below the exposed bottom of said still, said partitions normally extending upward to, but not in supporting contact with, the still bottom, the clearance spaces between said partitions and the still bottom being 40 normally open for the entrance of combustion gases, and of such order that when the bottom sags under high heat it will be supported on said partitions, and an offtake flue 45 in open communication with said compartments and said clearance spaces.

In testimony whereof I hereunto affix my signature.

ROBERT A. PORTERFIELD.
